LIFTING APPARATUS

George H. Jones, Lorain, Ohio, assignor to National Tube Company, a corporation of New Jersey

Application December 30, 1944, Serial No. 570,631

7 Claims. (Cl. 212—11)

This invention relates to improvements in lifting devices for articles such as ingot molds, the main object of the invention being to provide an arrangement whereby tilting or tipping of such articles during lifting thereof is prevented.

It is necessary in preparing ingot mold assemblies for reuse to lift the molds from the bases so that foreign matter can be removed therefrom. It sometimes happens with conventional apparatus comprising a pair of slings having the upper ends attached to the crane hook and having bights on the lower ends which are placed over oppositely disposed lugs on the molds, that one of such bights will slip off its lug, which causes the mold to tip or tilt since the crane operator cannot see that one of the bights is not properly positioned.

I have overcome the foregoing hazardous condition by the arrangement of my invention which briefly stated includes a looped sling having terminal work-engaging bights which is freely mounted intermediate its ends but includes means for preventing its withdrawal from its mounting, and a limit switch which prevents the crane block being lifted sufficiently high to cause an unengaged bight of the sling from contacting the withdrawal preventing means when the other bight is in engagement with the article to be lifted.

A preferred embodiment of this invention is illustrated in the accompanying drawing, wherein:

Figure 1 is an elevation;

Figure 2 is an enlarged elevation of the hook block; and

Figure 3 is a wiring diagram.

Referring more particularly to the drawing, the numeral 2 indicates a traveling bridge or girder which has wheels 4 at its opposite ends which are adapted to travel on suitably supported rails 6. A crane trolley 8 is mounted for rolling travel intermediate the ends of the girder 2 on wheels 10 and is provided with a hoisting drum 12, driven by an electric motor 14, the operation of which is controlled by an operator in the cab 16 at one end of the bridge or girder. A cable 18 cooperates with the drum 12 to lift a sheave 20 carried at the lower end thereof.

Suspended by a rod 17 from the frame of the trolley 8 in the path of movement of the sheave 20, is a limit switch 22 connected in series with a conventional motor control circuit 24 carrying electric power from power lines 26 to the motor 14. The limit switch 22 is operable to break the circuit 24 by a plunger member 28. Controls 28

for operating the motor 14 may also be connected in series in the control circuit 24 and are suitably located in the cab 16. Elevation of the sheave 20 above a predetermined height is thus prevented since the sheave 20 will contact the plunger 29 and break the motor control circuit.

Instead of having slings suspended from the hook 30 on the sheave 20, there is provided a specially designed hook block 40 attached to the hook 30 and carried thereby. This hook block comprises a pair of side frame members 42 having a pair of superposed sheaves 44 and 46 rotatably mounted therebetween. The hook block 40 has a pair of links 48 at the upper end thereof which are attached to an eye bolt 50 which is disposed on the hook 30. The eye bolt 50 is adjustably mounted between the links 48 as at 52. Accordingly, it is seen that the hook block 40 may be adjusted or rotated in a vertical plane 10 relative to the eye bolt 50. The side frames 42 are slightly twisted at approximately their mid-portions so that the sheaves 44 and 46 rotate in vertical planes but occupy vertical planes which are angularly disposed one with respect to the other.

The specific form of looped sling which I prefer is a continuous loop 60 freely suspended intermediate its ends on the hook block 40, the lower ends forming bights 62 and 64. The lower strand 30 of the sling passes over and is carried by the lower sheave 44 and the upper portion passes over and is carried by the sheave 46. The bight portions 62 and 64 may be formed of chain links or the like to provide sufficient resistance to the wear or abrasion caused by engagement with lugs on objects lifted thereby. The length of the sling 60 is such that if one of the loops engages a lug on an article to be lifted and the other loop is disengaged, the sheave 20 will actuate the limit switch 22 before the disengaged loop is drawn around the upper sheave 46. From this, it is seen that the sling is at least slightly more than twice as long as the upward movement of the sheave 20 after an article to be lifted is engaged by both bights and before the limit switch is engaged by the sheave 20.

In use, it is seen that the angular disposition of the sheaves 44 and 46 opens up or enlarges the bights 62 and 64 of the sling 60 so that they may more readily be engaged with the article to be lifted. Moreover, this angular disposition causes the sling 60 to frictionally engage the sheaves 44 and 46 so that if the sling becomes unbalanced the long end thereof will not draw the lighter end upward so as to make positioning thereof over a

lug difficult. Since the length of the sling and the disposition of the limit switch are correlated to prevent an unengaged end or bight of the sling to be drawn around the upper sheave before the article to be lifted is tilted by reason of its engagement with the other loop, it is impossible for the article to be tilted in case of disengagement of one of the bights.

While I have shown and described one specific embodiment of my invention, it will be understood that this embodiment is merely for the purpose of illustration and description and that various other forms may be devised within the scope of my invention, as defined in the appended claims.

I claim:

1. Lifting apparatus comprising suspension means, means for elevating said suspension means, stop means operable by said elevating means constructed and arranged to prevent elevating said suspension means above a predetermined point, a looped sling having terminal work-engaging bights freely carried by said suspension means, means to prevent said bights from being withdrawn from said suspension means, said sling being sufficiently long to cause said stop means to operate before one of said bights engages the withdrawal preventing means when only the other of said bights is attached to an article to be lifted.

2. Lifting apparatus comprising suspension means, means for elevating said suspension means, stop means operable by said elevating means constructed and arranged to prevent elevating said suspension means above a predetermined point, a looped sling having terminal work-engaging bights freely carried by said suspension means, means to prevent said bights from being withdrawn from said suspension means, said sling being more than twice as long as the upward movement of said suspension means after an article to be lifted is engaged by both bights and before said stop means is operated whereby said stop means will be operated before one of said bights will engage said withdrawal preventing means when only the other of said bights engages an article to be lifted thereby.

3. Lifting apparatus comprising elevating means, a motor for elevating said elevating means, a limit switch operable by the elevating means constructed and arranged to stop said motor to prevent elevation of said elevating means above a predetermined point, suspension means carried by said elevating means, a looped sling having terminal work-engaging bights freely mounted on said suspension means, means to prevent said bights from being withdrawn from said suspension means, said sling being more than twice as long as the upward movement of said suspension means after an article to be lifted is engaged by both of said bights and before said limit switch is operated by said elevating means whereby said limit switch will be operated before one of said bights will engage said withdrawal preventing means when only the other bight is attached to an article to be lifted thereby.

4. Lifting apparatus comprising suspension means, means for elevating said suspension means, stop means operable by said elevating means constructed and arranged to prevent elevation of said suspension means above a predetermined point, said suspension means comprising a pair of sheaves, a continuous looped sling freely suspended intermediate its ends on said

sheaves, one strand of said sling being carried by one of said sheaves and the other strand of said sling being carried by the other of said sheaves, the ends of said sling forming bights and being adapted to engage an article to be lifted on opposite sides thereof, said sling being sufficiently long to permit said stop means to operate before the bight on one end of the sling engages said upper sheave when only the other bight is attached to a lug on an article to be lifted.

5. Lifting apparatus comprising suspension means, means for elevating said suspension means, stop means operable by said elevating means constructed and arranged to prevent elevation of said suspension means above a predetermined point, said suspension means comprising a pair of superposed sheaves, said sheaves being rotatable in vertical planes, said planes being angularly disposed, a continuous looped sling freely suspended intermediate its ends on said sheaves, the upper strand thereof being suspended on the upper of said sheaves and the other strand being suspended on the lower of said sheaves, the lower ends of said sling forming terminal work-engaging bights adapted to engage the opposite sides of an article to be lifted, said sling being sufficiently long to permit said stop means to operate before one end of said bights engages said upper sheave when only the other bight is attached to an article to be lifted.

6. Lifting apparatus comprising elevating means, a motor for elevating said elevating means, a limit switch operable by the elevating means constructed and arranged to stop said motor to prevent elevation of said elevating means above a predetermined point, suspension means carried by said elevating means, said suspension means comprising a pair of sheaves, a continuous looped sling freely suspended intermediate its ends on said sheaves, one strand of said sling being carried by one of said sheaves and the other strand of said sling being carried by the other of said sheaves, the ends of said sling forming bights and being adapted to engage an article to be lifted on opposite sides thereof, said sling being sufficiently long to permit said stop means to operate before the bight on one end of the sling engages said upper sheave when only the other bight is attached to a lug on an article to be lifted.

7. Lifting apparatus comprising elevating means, a motor for elevating said elevating means, a limit switch operable by the elevating means constructed and arranged to stop said motor to prevent elevation of said elevating means above a predetermined point, suspension means carried by said elevating means, said suspension means comprising a pair of superposed sheaves, said sheaves being rotatable in vertical planes, said planes being angularly disposed, a continuous looped sling freely suspended intermediate its ends on said sheaves, the upper strand thereof being suspended on the upper of said sheaves and the other strand being suspended on the lower of said sheaves, the lower ends of said sling forming terminal work-engaging bights adapted to engage the opposite sides of an article to be lifted, said sling being sufficiently long to permit said stop means to operate before one end of said bights engages said upper sheave when only the other bight is attached to an article to be lifted.
